UNITED STATES PATENT OFFICE

2,562,442

COMPACT STEAM GENERATOR

William H. Attschuler and Basil Woynar, Chicago,
Ill., assignors to Combustion Engineering-Superheater, Inc., a corporation of Delaware

Application August 14, 1946, Serial No. 690,538

3 Claims. (Cl. 122—250)

1

The present invention relates to steam generators and particularly to a forced circulation boiler of high capacity especially adapted for use in supplying steam for car heating and similar purposes in a train.

The invention contemplates a boiler based upon the controlled forced circulation principle and operating at such water velocities and steam evaporating rates as to minimize scaling of the internal surfaces of the boiler, thus making it especially suited for use on rail lines where the water supply is of poor quality.

A feature of the present invention is the provision of a boiler which is of simple and compact construction despite its high steam generating capacity.

A second feature is a boiler having a convection section surrounding a furnace section on four sides and comprising a series of coils half of which may be dismounted as a unit to afford access to the furnace tubes.

Another feature resides in a boiler construction in which the convection section may be dismounted as a unit to afford ready access to defective furnace tubes to permit removal for replacement or repair without disturbing other furnace tubes.

The invention will be best understood upon consideration of the following detailed description of an illustrative embodiment thereof when read in conjunction with the accompanying drawings in which:

Figure 1 is a perspective view of a steam generating boiler embodying the present invention, parts being broken away to illustrate details of construction.

Figure 2 likewise is a perspective view with half of the convection surface and casing parts removed to afford access to the furnace wall tubes.

Figures 3 and 4 are sectional elevations on the correspondingly designated section lines in Figure 5.

Figure 5 is a sectional plan view of the boiler as viewed on the line 5—5 in Figure 4.

Figures 6 and 7 are respectively a plan and elevational view of one of the furnace wall coil units which is shown before it is shaped for installation in the furnace.

Figures 8 and 9 are plan and elevational views respectively of one of the convection tube coils before it is bent to shape for installation around the boiler furnace.

The steam generator of the present invention comprises a furnace 10 provided in its top wall 11 with the burners 12 for introducing fuel. All

2

four side walls of the furnace are completely lined with steam generating tubes 13 from the upper part of the furnace near the burners to adjacent the bottom of the furnace. As described later these tubes are formed into coils 31 to 38 with the lowermost coil resting upon refractory blocks 14 located at the corners of the furnace and spaced to provide therebetween a series of gas outlets 15, one in each side wall of the furnace chamber at its base. Above the supporting refractories 14 the furnace wall tubes 13 are enclosed within a steel plate 16 or other jacketing baffle separating the furnace chamber 10 from the convection passes 17 of the boiler. At their upper ends the gas passages 17 connect with individual offtake stacks 18, one at each of two diagonally opposite corners of the boiler. Located in the convection passes 17 are a series of steam generating tubes formed into roughly V-shaped coils designated 21 to 28. Feed water for the boiler is supplied by a pump 20 to a pair of horizontally disposed headers 30 and 40 which appear at the right hand side of Figures 4 and 5 and the left hand side of the perspective views, Figures 1 and 2. Each of the vertically disposed convection coils 21 to 24 is connected at one end to the header 30 while the remaining coils 25 to 28 are connected at one end to the header 40.

All of these coils 21 to 28 comprise a series of parallel tube sections superimposed in a vertical plane and interconnected for serial fluid flow as shown in Figure 9 by closely coupled integrally forged return bends 51 or loosely coupled bends or U-loops 53 formed from the tubes. The return bends 51 and loops 53 alternate serially with respect to fluid flow and are located first at the right and then the left side of the coil so that part of the coil may in effect be folded back and nested within the remainder due to the wide spacing of the loops receiving closely coupled tubes so that the inlet 60 and outlet 61 of the coil may both be located at the top part thereof. Subsequent to joining of the tubes to form this grid-like coil, the inlet and outlet ends 60 and 61 thereof are bent in the same direction at an angle of approximately 45° and the whole coil is then bent at approximately the middle thereof on a 90 degree angle thereby forming the V-shaped coils which appear in plan in Figure 5. The ends 60 and 61 project outwardly in opposite directions for connection respectively to the water headers 30 or 40 and to the inlet ends 65 of the furnace wall coils 31 to 38 through intermediate connector tubes 41 to 48 leading thereto as will be described.

The furnace wall coils 31—38 before shaping to the rectangular contour of the furnace appear as shown in Figures 6 and 7, each comprises three parallel tubes 63 interconnected for series fluid flow by a pair of return bends 64 with projecting inlet and outlet end sections 65 and 66 bent at 45° angles. The furnace wall tubes are then bent to form a square loop as is most clearly shown in Figure 2 with the inlet and outlet sections disposed one above the other in parallel relation as shown in Figures 1 to 5. The outlets 66 connect with the collecting header 68. The inlet end 65 of each furnace coil is connected to the lower end of a connector tube 41 to 48 leading from and connected at its upper end to the outlet end 61 of one of the convection coils 21 to 28. Thus there are eight completely independent circuits through the boiler each leading from one of the water inlet headers 30 or 40 through a convection coil 21—28 and then via connecting tubes 41 to 48 to a coil 31 to 38 lining the furnace wall and from the outlet ends 66 of the latter into the collecting header 68. Orificed members of different sizes may be embodied in the inlet portions 60 of the coils 21 to 28 for restricting or controlling flow to effect a desired distribution of water among the circuits.

The construction described above is for a high steam generating surface which has been compressed into a relatively small space due to the special formation of the coils 31—38 lining the furnace walls and the specially shaped convection coils 21—28 which lie between the furnace and the outer wall of the boiler. Despite the enclosure of the furnace wall tubes within the convection bank, access may readily be had to all of the furnace wall tubes 31 to 38 for inspection or to repair or replace a damaged coil. The convection section of the boiler and the enclosing casing are divisible on a diagonal line A (Figure 1) so that half of the casing and convection section may be detached from its remaining half and thereby afford access to the coils 21 to 24 that form the furnace wall along the two contiguous sides as appears in Figure 2. To effect this separation of half of the casing and the enclosed convection surface and related water inlet header 40 or 30 the casing plate 80 and 81 enclosing the collecting header are removed to afford access to the joints of the connector tubes 41 to 48 with the convection and radiant coils. It is necessary only to break the joints 69 (Figure 4) between the inlet ends 65 of half the radiant coils (as 31 to 34) and the lower ends of the connecting tubes 41 to 44 leading from the convection coils 21—24. The connecting tubes 41 to 44 remained joined to the outlets 61 of the related convection coils 21—24 and are moved with them away from the furnace wall. Externally of the boiler, the only connection which has to be broken is that between the water feed line 83 and the related inlet header 30 or 40. When either half of the convection surface has been removed as described above, and baffle plate 16 dismounted any one of the four superposed radiant coils (as 21—24) on that side of the boiler may be separately removed simply by breaking the connection between its outlet end 66 and the collecting header 68, the inlet ends 65 of these coils being no longer attached because of the removal of the related connecting tubes (as 41 to 44) with the associated convection coils (31—34).

Although details of construction, such as casting parts, clips, spacers and supports for the tubes and coils have not been described in detail

it is to be understood that such elements are provided where required.

What we claim is:

1. In a boiler; means forming an elongated furnace chamber rectangular in cross-section and a pair of surrounding gas passages parallel to its major axis of generally V-shape one at each side of a diagonal through said chamber and in communication with the latter at one end thereof; a plurality of convection heated elements comprising tubing looped to form a coil with parallel reaches extending back and forth across the gas passages throughout the length thereof and each coil being bent to generally V-shape and having its inlet and outlet portions projecting outwardly from the related gas passages at opposite ends of said diagonal of the furnace chamber; water supply header means disposed exteriorly of said gas passages at one end of said diagonal of the furnace and connected to the inlet ends of said convection coils; a plurality of radiantly heated steam generating units lining the wall of said furnace each comprising tubing shaped to form a rectangular coil conforming to the wall contour of said furnace and having both inlet and outlet leads projecting laterally from the coil at one corner thereof located at the opposite end of said diagonal of said furnace; tubular means interconnecting the outlet ends of each convection coil at said opposite end of said furnace diagonal to the inlet end of one of said furnace coils; and a fluid collecting header extending parallel to the main axis of the furnace along the corner at that end of the diagonal of the furnace from which the leads to said furnace coils project and connected to the outlet ends of said furnace coils.

2. In an upright boiler; means forming an elongated furnace chamber and a surrounding gas passage paralleling its vertical axis and in communication with the latter at one end thereof; a plurality of convection coils located in said passage in nested relation transversely thereof each comprising tubing bent to fit transversely against approximately half of the wall of said chamber transversely thereof and having inlet and outlet portions projecting outwardly from the gas passage at opposite sides of said furnace chamber; water supply means disposed exteriorly of said gas passage at one side of the furnace and connected to the inlet ends of said convection coils; a plurality of radiantly heated steam generating coils lining the wall of said furnace each comprising tubing shaped to form a coil conforming to the entire interior wall contour of said furnace and having both inlet and outlet leads projecting laterally from the coil at the opposite side of said furnace; tubular means interconnecting the outlet ends of each convection coil to the inlet end of one furnace coil; and a fluid collecting header extending parallel to the vertical axis of the furnace along the edge at said opposite side of the furnace from which the leads to said furnace coils project and connected to the outlet ends of said furnace coils.

3. In a boiler; means forming an elongated furnace chamber and in communication with one end thereof a pair of gas passages, one extending at each side of said chamber parallel to its major axis and complementing each other to substantially surround said chamber; convection heated coils mounted in said gas passages in nested relation from the inner to the outer walls thereof comprising tubing bent to conform to the contour

of the cross section of the gas passage in which it is located so that the coils in the two passages substantially fill said passages and complement each other to substantially surround said furnace chamber, said coils having their inlet and outlet portions projecting outwardly from the related gas passages at opposite sides of said furnace chamber; water supply header means disposed exteriorly of said gas passages at one side of said furnace and connected to the inlet ends of said convection coils; a plurality of radially heated steam generating units lining the wall of said furnace each comprising tubing shaped to form a coil conforming to the entire inner wall contour of said furnace and having inlet and outlet leads projecting laterally from the coil at the side of said furnace opposite to that at which said water supply header is located; tubular means disposed at said opposite side of said furnace interconnecting the outlet ends of each convection coil to 20

the inlet end of one of said furnace coils; and a fluid collecting header extending parallel to the main axis of the furnace along the side from which the outlet leads of said furnace coils project and connected to the outlet ends of said furnace coils.
